US00D838840S

(12) **United States Design Patent** (10) Patent No.: **US D838,840 S**
(45) Date of Patent: ** Jan. 22, 2019

(54) **INJECTOR DEVICE**

- (71) Applicant: **West Pharma. Services IL, Ltd.**, Ra'anana (IL)
- (72) Inventors: **Oz Cabiri**, Macabim-Reut (IL); **Reuven Y. Filman**, Tel Mond (IL); **Boris Degtiar**, Modiin (IL); **Ofer Zick**, Tikva (IL)
- (73) Assignee: **West Pharma. Services IL, Ltd.**, Ra'anana (IL)
- (**) Term: **15 Years**
- (21) Appl. No.: **29/643,589**
- (22) Filed: **Apr. 10, 2018**

Related U.S. Application Data

- (63) Continuation of application No. 29/605,061, filed on May 23, 2017, now Pat. No. Des. 817,481, which is a continuation of application No. 29/604,616, filed on May 18, 2017, now Pat. No. Des. 811,583, which is a continuation of application No. 13/667,739, filed on Nov. 2, 2012, now Pat. No. 10,071,198, and a continuation of application No. 13/472,112, filed on May 15, 2012, now Pat. No. 10,071,196, which is a continuation of application No. 15/395,166, filed on Dec. 30, 2016, which is a continuation of application No. 13/892,905, filed on May 13, 2013, now Pat. No. 9,572,926, which is a continuation of application No. 13/272,555, filed on Oct. 13, 2011, now Pat. No. 8,465,455, which is a continuation of application No. (Continued)

CLAIM

The ornamental design for an injector device, as shown and described.

DESCRIPTION

FIG. 1 is a front, right side isometric view of an injector device in accordance with our new design; FIG. 2 is a front elevational view thereof; FIG. 3 is a rear elevational view thereof; FIG. 4 is a left side elevational view thereof; FIG. 5 is a right side elevational view thereof; and, FIG. 6 is a top plan view thereof. The broken lines in the drawings depict portions of the injector device that form no part of the claimed design.

1 Claim, 4 Drawing Sheets

Related U.S. Application Data

12/559,563, filed on Sep. 15, 2009, now Pat. No. 8,157,769, said application No. 29/604,616 is a continuation of application No. 15/132,740, filed on Apr. 19, 2016, now Pat. No. 9,764,092, which is a continuation of application No. 14/553,399, filed on Nov. 25, 2014, now Pat. No. 9,522,234, which is a continuation of application No. 14/258,661, filed on Apr. 22, 2014, now Pat. No. 9,149,575, which is a continuation of application No. 13/521,167, filed as application No. PCT/US2011/021604 on Jan. 19, 2011, now Pat. No. 8,915,882.
